UNITED STATES PATENT OFFICE.

JOHN J. KANE, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

TIME-LIMIT APPARATUS.

1,418,803.

Specification of Letters Patent. Patented June 6, 1922.

Application filed July 30, 1917. Serial No. 183,989.

To all whom it may concern:

Be it known that JOHN J. KANE, a citizen of the United States, residing at Milwaukee, in the county of Milwaukee and State of Wisconsin, has invented a certain new and useful Improvement in Time-Limit Apparatus, of which the following is a specification.

This invention relates in general to devices operative to effect desired results after a certain time limit, and has more particular relation to devices of this general character that are electrically operable and in which the time element involved in the effective operation of the device is variable in a desired manner.

In electrical power systems, it is desirable to effect interruption or other control of a circuit when the same is subjected to abnormal operating conditions for such a period of time that damage might result to the generators supplying the circuit or to any control apparatus connected thereto. The period of time during which the apparatus can safely be subjected to abnormal conditions is ordinarily variable depending upon the character or intensity of such abnormal conditions. In some cases it is desirable to permit the line to remain intact for a period of time that varies inversely as the value of an abnormal condition up to a certain predetermined value, and, for all higher values of the abnormal condition, it is desirable that the circuit be interrupted after a time interval which is comparatively small and substantially constant or definite but which, nevertheless, insures freedom from interruption due to momentary disturbances. In order that the operation of several of such time limit devices may be selective as to the time interval involved when the abnormal conditions are of the higher values, provisions are usually made for preliminarily selecting or adjusting this minimum time interval so that only the device nearest the source of the disturbance will operate.

It is an object of this invention to provide a time limit apparatus of improved design and construction and capable of effective operation after a variable period of time on the occurrence of certain controlling conditions.

It is a further object of this invention to

provide a time limit apparatus of improved design and construction and capable of effective operation after a variable period of time on the occurrence of certain controlling conditions, and wherein, for other controlling conditions, the time interval involved in the effective operation of the apparatus is substantially constant or definite.

It is a further object of this invention to provide an electrically operable time limit apparatus of improved design and construction and capable of effective operation when subjected to abnormal controlling conditions for a period of time that varies inversely as the intensity of the abnormal conditions up to a certain value thereof and is substantially constant or definite and of appreciable duration for abnormal conditions of greater intensities.

These and other objects and advantages are attained by this invention, the various novel features of which will be apparent from the description and drawings, disclosing one embodiment of such invention, and will be particularly pointed out in the claims.

In the accompanying drawings:

Fig. 1 is a diagrammatic disclosure of an embodiment of this invention, a variable time limit relay device being shown in partial sectional elevation.

Fig. 2 is a plan view of a portion of the apparatus shown in Fig. 1.

Fig. 3 is a sectional plan view on the line 3-3 of Fig. 1.

In the embodiment of the invention illustrated, a circuit-breaker 10 is disposed in the line circuit *a*, *b*, the circuit-breaker being held in closed position by means of a latch 11. The latch 11 may be tripped to permit opening of the circuit-breaker 10, on closure of the circuit of the tripping coil 12 with which the latch is electromagnetically associated. The circuit of the tripping coil 12 may be supplied from any suitable source, here shown as a local battery, and may be closed by means of a hand switch 13, or may be closed automatically through operation of the relay device R embodying features of this invention.

The relay R has the general form of a solenoid magnet having an energizing coil or winding 14, here shown as being in series with one side of the line circuit *a*, *b*. The

coil 14 has associated therewith and in fixed position relative thereto a tube 15 of non-magnetic material, such as brass, the tube being closed in a liquid-tight manner at its upper end by a disc-like closure 16, preferably of insulating material, and being similarly closed at its lower end by a disc-like closure 17. Mounted for free reciprocation in the tube 15 is a magnetizable core 18 of a compound character and movable in response to sufficient energization of the winding 14. This core comprises a main plunger portion 19, in the form of an inverted cup having a head portion 21 and a cylindrical extension 22 projecting downwardly from the head portion and of considerably less cross-sectional area than the head, and an auxiliary portion 23 freely reciprocable within the cylindrical extension 22. This auxiliary core member 23 is provided with comparatively large openings 24 extending throughout its full length, and is normally urged to a position away from the head portion by means of a spring 25 disposed between the lower side of said head and the upper side of the auxiliary core member. The normal position of the core 23 is determined by an abutment 26 carried by a bushing 27, preferably detachably threaded into the lower end of the cylindrical part 22 of the main core member. This bushing 27 is preferably provided with spider arms 28 carrying a portion 29 which constitutes an abutment for the end of a hand screw 31 adjustable through the lower end closure 17 to vary the initial or normal position of the bushing 27, the main core member 19 connected therewith and the auxiliary core member 23 carried thereby.

The core 18 is normally held in the position indicated by gravity, although a comparatively light spring 35 may be provided to assist or insure the ready movement of the core to the position indicated subsequent to operation thereof. The casing 15 may be filled with oil or other insulating fluid, as indicated, a comparatively small port 37 being provided through the head portion 21 to permit the fluid to pass therethrough to cause such equalization of the pressure on the two sides of the head portion as will allow upward movement of the core when the same is sufficiently energized by the winding 14. The speed of this upward movement of the core is determined by the rate at which oil may pass from the upper side of the head 21 to the lower side thereof. It will be obvious that by providing a passage through the head portion of the required size, comparatively any speed of movement of the core may be obtained. The head portion 21 is also provided with a comparatively large port 38 having a seat at its upper end normally closed by a ball check valve 39. During the upward movement of

the core, the pressure developed on the upper side of the core holds the valve on its seat, but the core is permitted to travel downward to the position shown in a comparatively short space of time.

To permit movement upward of the core 18 at different speeds an additional port 41 is provided in the head 21, preferably at the center thereof, this port being preferably of conical shape to provide a seat for a cone-shaped valve 42 adjustably mounted upon a rod or stem 43 and held in adjusted position thereon by a lock nut 45. This valve 42 is provided with guide vanes 47 engageable with the inner side of a cylindrical guide bushing 48 attached to or integral with the head portion 21 of the core, which serve to guide the valve in its movement to and from its seat. The lower end of the valve rod or stem 43 is disposed in engagement with or comparatively close to the upper end of the auxiliary core 23, when the latter is in its lowest position, as indicated, and in position to be engaged thereby and moved upward when the auxiliary core member is moved upward relatively to the main core member 19, against the action of gravity and the spring 25.

An adjustable stop 51, preferably in the form of a rod adjustably threaded through the head 21 and locked in position relatively thereto by a lock nut 52, serves to adjustably limit the upward movement of the auxiliary core member 23 relative to the main core member 19.

A rod or extension 56 is provided on the upper side of the head portion 21 and serves, when the main core is drawn upward, to engage the movable contact 61 of a circuit closer in the circuit of the tripping coil 12. This movable contact 61 is adapted to be moved into engagement with a fixed contact 62 of the circuit closer to cause closure of the circuit of the tripping coil 12. The supports for the contacts 61 and 62 are mounted and insulated from each other in the upper closure 16 of the tube 15.

Instead of having the energizing winding 14 connected directly in series with the line circuit *a*, *b*, an adjustable rheostat 65 may be provided in shunt to the winding to thereby reduce and permit variation of the proportion of main line current passing through the winding.

With the relay R operatively connected relatively to the line circuit *a*, *b*, to effect control of the circuit-breaker 10, and the line current and current in the winding 14 normal, the parts of the relay are in the positions indicated. On the occurrence of current of a certain predetermined value, which is just capable of creating sufficient flux to cause the core 18 to move upward toward the center of the energizing winding 14, the main core member 19 moves upward, the

speed of such movement being determined by the time required for the passage of fluid from the upper side of the core through the port 37 to the lower side thereof.

5 Current of this particular value is not intended to have any appreciable effect in causing upward movement of the auxiliary core member 23 relative to the main core 19 and against the action of the spring 25. Of course, the auxiliary core member is carried upward with the main core member 19, being moved through the mechanical engagement with the abutment 26 on the bushing 27.

When the core reaches a certain position 15 in its upward travel, the rod 56 engages the movable contact 61 and causes closure of the circuit of the tripping coil 12 and the consequent opening of the circuit-breaker 10. The winding 14 being deenergized through opening of the circuit-breaker 10, the core 18 is urged downward by gravity and the spring 35, this downward movement being a great deal faster than the upward movement, since fluid may pass comparatively quickly from 20 the lower side of the core, through the relatively large port 38 and past the ball valve 39, to equalize the pressure on both sides of the core. During this operation of the relay at a current value corresponding to the low- 25 est value at which the core is effectively operative, the flux produced by the energizing winding 14 in the head portion 21 of the main core 19 may be more or less effectively carried by the cylindrical core portion 22, 30 the flux across the gap between the head portion 21 and the auxiliary core member 23 not being sufficient to cause movement upward of the auxiliary core member, that is, movement upward relative to the main core 35 member and against the action of the spring 25.

However, when the relay winding is subjected to current of a higher value, the flux created thereby is sufficient to substantially 40 saturate the cylindrical core part 22 and to exert a pull on the auxiliary core 23, across the gap between the latter and the head 45 21, sufficient to cause the auxiliary core to move upward to a greater or less extent against 50 the action of gravity and the spring 25. Obviously, there is nothing to cause any appreciable retardation of the auxiliary core member 23 in its upward movement relative to the main core member 19, since the openings 55 24 through the auxiliary core member are of such size as to permit free and ready equalization of pressure on the two sides of this auxiliary core member and thus permit comparatively quick movement upward of the 60 latter member. The upward movement of the main core member being retarded by the body of oil on the upper side thereof, such member acts as a relatively fixed abutment for the spring 25 and the latter is com- 65 pressed more or less and the auxiliary core

member 23 moved upward to a greater or less degree, depending on the value of the current in the winding 14. Depending upon the position of the lower end of the valve rod 43, the same is engaged by the auxiliary core member 23 when the relay is energized by current corresponding to an overload of a certain value. In its upward movement, the auxiliary core member 70 engages the rod 43 and lifts the valve 75 42 from its seat to a greater or less extent, depending upon the value of the overload. Opening of this valve 42 provides an additional port through the head 21, which has the effect of correspondingly decreasing the 80 time required to move the rod 56 into engagement with the circuit closing contact 62.

By proper determination of the size of the opening provided by the valve 42, the strength of the spring 25 and the dimensions of the magnetizable core members, the auxiliary core member 23 may be effective to cause such variation in the time interval required to produce closure of the circuit of the tripping coil 12 as may be desired. The higher the overload, the greater amount of flux is produced by the winding 85 14 and the greater is the flux across the gap between the head 21 and the auxiliary core 23, and, hence, the greater the tractive effort 90 on the latter, with a corresponding variation in the opening of the valve 42, and a consequent decrease in the time interval 95 elapsing before closure of the contacts 61, 62 of the circuit of the tripping coil 12. 100

It will be apparent that this variation of the time interval is inverse to the variation in the degree of the overload up to that overload value which causes the production of sufficient tractive effort on the auxiliary 105 core 23 to cause the same to be moved upwardly, against the action of the spring 25, into engagement with the stop 51. This stop 51 determines the upper limit of movement of the auxiliary core member 23, and, consequently, the maximum opening of the valve 42. All overloads of a value higher 110 than that which causes movement of the core 23 into engagement with the adjustable stop 51 have no further effect in increasing the size of the effective opening through the port 41 past the valve 42, and, hence, have no further effect in causing appreciable decrease in the time interval involved in the closure of the circuit of the tripping coil 12 115 and opening of the circuit-breaker 10. Obviously, this maximum opening of the valve 42 with its consequent minimum time interval may be readily varied, as for the purpose of rendering several relays selective, merely 120 by adjustment of the stop rod 51.

While overloads higher than the lowest one which causes maximum upward movement of the auxiliary core 23 may produce somewhat greater tractive effort on the core 130

21 and thus put the fluid on the upper side of the head 21 under slightly greater pressure, nevertheless, there is no appreciable variation in this minimum time interval from this cause. In order to reduce to a minimum this variation in the time interval occurring with the higher overload values, the apparatus may be of such design that the head portion 21 of the core becomes fairly well saturated on the flow of current in the winding 14 of a value which causes movement of the auxiliary core 23 to its upper limiting position.

It will be apparent that the value of current in the main line at which the relay is first operative may be varied either by the adjustment of the rheostat 65 to vary the proportion of line current flowing in the energizing winding 14, or by adjustment of the hand screw 31 to adjust the initial position of the core 18.

The bushing 27 may be adjustable to any desired degree in the lower end of the cylindrical sleeve 22 of the core to thereby adjust the initial position of the auxiliary core member 23 relative to the main core member 19, such adjustment varying the initial gap between the auxiliary core 23 and the head 21 of the main core. The rod 43 may be correspondingly adjusted relatively to the valve 42 to maintain the same or a slightly different relation between the lower end of the rod and the auxiliary core member 23.

It will be apparent that in accordance with this invention an electrically operated time limit device is provided which is effective to cause a desired controlling operation on the occurrence of an overload on the circuit to be controlled, the time element involved varying inversely as the degree of the overload up to a certain point and, beyond the latter point, being substantially constant or definite.

It should be understood that it is not desired that the invention claimed be limited to the exact details of construction shown and described, for obvious modifications will occur to a person skilled in the art.

It is claimed and desired to secure by Letters Patent:

1. In a circuit-controlling apparatus, relatively movable contacts, an overload coil, a core member movable into said coil, means for retarding the movement of said core member into said coil, and a member of magnetic material which is movable independently of said first member and in response to energization of said coil to vary the retardation of said core member.

2. In a circuit-controlling apparatus, relatively movable contact members, and means for causing actuation of one of said contact members, said actuating means comprising an overload coil, two mechanically associated and relatively movable armatures for said

coil having portions magnetically in series in the normal magnetic circuit of said coil, and means for retarding the movement of one of said armatures, the other of said armatures being effective to vary the retardation of said first armature to thereby cause effective operation of said actuating means to occur after a time interval which is an inverse function of the degree of the overload.

3. In combination, a switch-actuating member, means for causing actuation of said member, said means comprising an electromagnet having an element of magnetic material movable in response to abnormal circuit conditions above a certain degree, and instrumentalities for causing effective movement of said element to occur after a time interval that varies inversely as the abnormality of said conditions, said instrumentalities including an electromagnetically-actuated element having a portion magnetically in series with and mechanically dependent upon said first element.

4. In combination, a movable element of magnetic material, electromagnetic means effective, when energized to a predetermined degree, to cause effective operation of said element, fluid-controlled means for retarding the operation of said element, a second electromagnetically-actuated element magnetically and mechanically associated with said first element and capable of movement relative thereto and operative to control the movement of said first element to cause energization of said electromagnetic means to a different degree to produce effective operation of said first element after a variable time interval.

5. An automatic overload circuit-breaker comprising a movable circuit-controlling member, an energizing winding, two cooperative, magnetically associated and relatively movable elements of magnetic material operable through electromagnetic effects produced by said winding, movement of one of said elements in response to said coil being damped and movement of the other element being undamped, movement of said undamped element controlling movement of the damped element under conditions of moderate overload to thereby vary the time elapsing in the effective operation of said damped element, and means controlled by said damped element for causing actuation of said circuit-controlling member.

6. A time-limit device comprising a magnetizing coil, a casing containing a body of fluid, a movable, variably retarded, magnetizable means comprising relatively movable parts within said casing and adapted to travel in the magnetic field of said coil, the time interval involved in the operation of said device varying in response to the relative movement between said parts.

7. A time-limit device comprising a magnetizing coil, a casing containing a body of fluid, a variably retarded, movable magnetizable means within said casing and comprising relatively movable parts, the effective speed of motion of said means being dependent upon the relative movement between said movable parts.

8. A time-limit device comprising a magnetizing winding, a casing containing a body of fluid, a movable, retarded, magnetizable core member within said casing and operable in response to energization of said winding, and means within said casing and operative in response to predetermined conditions of the energization of said winding for varying the retardation of said core member.

9. A time-limit device comprising a magnetizing winding, a casing, a magnetizable core member movable within said casing in response to energization of said winding, fluid-controlled means within said casing for retarding the movement of said core, and means also responsive to the energization of said winding for varying the rate of retardation of said core.

10. A time-limit device comprising a magnetizing winding, a magnetizable core movable in response to energization of said winding, means for retarding said core, said core comprising relatively movable parts, and means effective to permit simultaneous movement and prevent appreciable relative movement of said parts on energization of said winding by current of less than a certain value and to permit relative movement of said parts on energization of said winding by current of a value greater than said latter value, relative movement between said parts being effective to cause variation in the retardation of said core.

11. In a time-element apparatus, the combination of an element movable in response to controlling conditions and provided with an orifice, a body of fluid which movement of said element tends to force through said orifice, and means mechanically associated with said element for varying the size of the orifice in response to the same controlling conditions.

12. In a time-element device, a dashpot having relatively movable parts and an orifice, electromagnetic means comprising an energizing winding responsive to controlling conditions for causing relative movement between said parts, and means magnetically and mechanically associated with one of said relatively movable parts and responsive to the same controlling conditions for varying the size of said orifice.

13. A selective time-limit controlling device for an electric switch, including in combination a controlling magnet responsive to an overload current, operating means for

said switch actuated thereby, means for retarding said operating means, and means responsive to the energization of said controlling magnet for controlling said retarding means.

70

14. A selective time-limit controlling device for electric switches, including a solenoid responsive to an overload current, operating means for the switch actuated thereby, a fluid-controlled timing device to regulate the speed of motion of said operating means, a regulating valve for said timing device, and means mechanically associated with said operating means and responsive to the energization of said solenoid for automatically adjusting said valve according to the strength of the overload.

75

15. An apparatus for controlling an electric circuit, comprising mechanism operative to exert a controlling effect on said circuit, and time-limit means responsive to an abnormal condition of said circuit and operative to cause operation of said mechanism after a period of time which is an inverse function of the intensity of the abnormal condition for values thereof up to a certain point and a desired effective period of time for all values of the abnormal condition, said time-limit means comprising an electromagnet having an energizing winding and a retarded core therefor, and means magnetically associated with said core and responsive to energy due to said winding for varying the speed of movement thereof.

90

16. In combination, a circuit-controlling device, and time-limit means responsive to abnormal electrical conditions and operative to cause operation of said circuit-controlling device after a time interval that is an inverse function of the abnormality of said conditions up to a certain value thereof and constitutes a desired effective time interval for all higher values of the abnormal conditions, said time-limit means comprising an electromagnet having an energizing winding and a retarded core therefor, and means magnetically and mechanically associated with said core and variably responsive to said abnormal conditions for varying the retardation of said core.

100

17. A time-limit controlling apparatus comprising an electromagnetic device including an energizing winding and a magnetizable core movable in the magnetic circuit of said winding, said core comprising relatively movable magnetizable elements, one of said elements being operative to cause the desired circuit-controlling operation, means for retarding movement of said member, a second one of said core members being variably movable relatively to the first member in response to energization of said winding to control the retardation of said first member.

110

18. A selective time-limit apparatus for

130

- controlling electrical circuits, comprising an electromagnetic device including an energizing winding and a magnetizable element movable in response to energization of said winding to effect a circuit-controlling operation, and means magnetically and mechanically associated with said magnetizable element and variably responsive to energization of said winding and effective to cause the speed of movement of said magnetizable element to vary inversely as the degree of energization of said winding.
19. A selective time-limit apparatus for controlling electrical circuits, comprising an electromagnetic device including an energizing winding and a magnetizable element movable in response to energization of said winding to effect a circuit-controlling operation, and means magnetically and mechanically associated with said magnetizable element and variably responsive to energization of said winding and effective to cause the speed of movement of said magnetizable element to vary inversely as the degree of energization of said winding up to a predetermined value of said energization and to be substantially constant or definite for all values of energization above said predetermined value.
20. A selective time-limit apparatus for controlling electrical circuits, comprising an electromagnetic device including an energizing winding, a magnetizable element movable in response to energization of said winding to effect a circuit-controlling operation, means for retarding free movement of said magnetizable element, and means mechanically associated with said magnetizable element and magnetically responsive to energization of said winding to control the retardation of said magnetizable element so as to cause effective operation of said element to occur after a time interval that varies inversely as the degree of said energization.
21. A time-limit controlling apparatus for electric circuits, comprising an electromagnetic device including an energizing winding and a magnetizable core movable in the magnetic circuit of said winding in response to overloads on the circuit to be controlled, said core comprising relatively movable members, and instrumentalities for insuring simultaneous movement of said members on the occurrence of lower overload values and relative movement between said members on the occurrence of higher overload values to thereby effect a variation in the retardation of said core in its circuit-controlling operation.
22. A time-limit controlling apparatus comprising an electromagnetic device including an energizing winding and a magnetizable core member movable in the magnetic circuit of said winding, a closed fluid-containing receptacle in which said core is movable, a bypass through said core, a valve for controlling the flow of fluid through said bypass, a magnetizable member carried by said core member and capable of movement relative thereto on sufficient energization of said winding and operative to vary the opening of said valve to thereby vary the retardation of said core.
23. A selective time-limit controlling device for electric switches, including in combination overload responsive means for operating a switch comprising an energizing winding, and an element movable in response to a predetermined degree of energization of said winding, a device for retarding said operating means, and means responsive to energization of said winding to a degree corresponding to a predetermined overload for variably adjusting said retarding device and causing the time interval involved in the effective operation of said operating means to vary inversely as the degree of the overload.
24. A selective time-limit controlling device for electric switches, comprising overload responsive operating means for a switch comprising an energizing winding, and an element movable in response to energization of said winding to a degree corresponding to a predetermined overload, a retarding device for said operating means, and means responsive to energization of said winding to a degree corresponding to overload conditions for variably adjusting the time interval in the effective operation of said operating means up to a certain overload value and for maintaining a substantial and desired effective time interval for all higher overload values.
25. A time limit device, comprising an energizing winding, a variably retarded member movable in response to magnetic effects due to said winding, and a movable element responsive to energizing effects produced by said winding for causing the retardation of said member to vary inversely as the energization of said winding.
26. In a circuit controlling device, fixed and movable contacts, a coil adapted to carry current proportional to the current in the circuit to be controlled, a member movable in response to inductive effects produced thereon by said coil, said member being operative to cause the operation of said circuit controlling device wholly through inductive effects on the occurrence of abnormal conditions in said circuit, and means for causing effective operation of said member to occur after a time interval that varies inversely as the intensity of the abnormal conditions, said means comprising an element movable along substantially the same path as said member in response to inductive effects produced by said coil.
27. A time limit device, comprising a mag-

netizing coil, a magnetic circuit for said coil comprising two movable members having portions of their normal magnetic circuit magnetically in series with each other in the 5 normal magnetic circuit produced by said coil, means for retarding movement of one of said members, the other of said members being mechanically associated with the first member and being movable independently 10 thereof upon energization of said coil to a value above a predetermined point to thereby vary the retarding effect upon said first member.

28. A selective time limit apparatus for 15 controlling electrical circuits, comprising an electromagnetic device including an energizing winding, and an element movable in response to energization of said winding to effect a circuit controlling operation, and 20 means magnetically and mechanically associated with said element and variably responsive to energization of said winding and effective to cause the production of a time interval in the effective operation of said 25 apparatus that varies inversely as the degree of energization of said winding up to a predetermined value and constitutes a desired

effective and substantially definite time interval for values of said energization above said predetermined value. 30

29. A retarded time limit device, comprising a magnetizing coil and a magnetic circuit for said coil comprising a plurality of members having portions magnetically in series in the normal magnetic circuit of said coil 35 and relatively movable in substantially the same path, one of said members being effective to cause the time interval involved in the effective operation of another of said members to vary inversely as the degree of 40 energization of said coil.

30. In a controlling apparatus, an electromagnetically responsive device comprising an energizing winding, and an operating element movable in response to a predetermined energization of said winding, and means for variably retarding said operating element to a degree dependent upon the energization of said winding, said latter means including an element responsive to the energization of said winding. 45 50
